DEGRADATION OF UNSATURATED FATTY ACIDS

Werner Stein, Dusseldorf-Holthausen, and Horst Hennig, Dusseldorf-Oberkassel, Germany, assignors to Henkel & Cie. G.m.b.H., Dusseldorf-Holthausen, Germany, a German corporation

No Drawing. Application February 5, 1957
Serial No. 638,216

9 Claims. (Cl. 260—413)

This invention relates to new and useful improvements in the degradation of unsaturated fatty acids.

Alkali soaps of unsaturated fatty acids, which are free from alcoholic hydroxyl groups may be degraded to soaps of the corresponding saturated fatty acids containing 2 less carbon atoms than the initial unsaturated fatty acids by heating at a temperature above about 280° C. and preferably at a temperature of about 320° C. in the presence of an alkali hydroxide in accordance with the well-known method of Varrentrapp. The degradation occurs with the evolution of hydrogen and the reaction may be catalyzed with cadmium or cadmium compounds.

One object of this invention is an improved method for the above-described degradation. This, and still further objects will become apparent from the following description:

In accordance with the invention, it has now been found that the degradation of unsaturated fatty acids which are free from alcoholic hydroxyl groups by heating in the presence of an alkali is catalyzed by lead, bismuth, or thallium. In accordance with the invention the heating in the presence of the excess alkali is therefore effected in the additional presence of at least one of lead, bismuth, and thallium. The catalyst metal, i.e., the lead, bismuth, or thallium may be added in the form of a mixture, alloy, or a compound of the metal.

The process in accordance with the invention is suitable for the degradation of any of the known, unsaturated, fatty acids which could conventionally be degraded by heating in the presence of an excess of alkali. The unsaturated fatty acids are subjected to the degradation in the form of their alkali soaps, and the starting materials in the process in accordance with the invention include any of the alkali soaps of unsaturated fatty acids which are free from alcoholic hydroxyl groups and which may be derived from fats of vegetable or animal origin or from any desired mixture containing unsaturated fatty acids. There may also be used fatty acid fractions from which the saturated portions have been removed to a greater or lesser extent by conventional methods.

The degradation reaction is believed to occur with a migration of the double bond toward the carboxyl group and a splitting off of acetic acid. An excess of alkali which theoretically amounts to one times the average number of double bonds per molecule in mols of alkali hydroxy per mol of fatty acid is required for binding the acetic acid thus produced. In practice, however, the amount of alkali used can vary widely from this theoretically required value, and it is even possible to use a quantity of alkali which is considerably less than the theoretical value. In general, however, the quantity of alkali hydroxide should be at least about 50% of the quantity theoretically required. This applies in particular to the partial degradation of fatty acid mixtures having a large portion of unsaturated fatty acids with more than one double bond in the molecule. As the unsaturated

2

fatty acids having multiple double bonds are more easily degraded than those having a single double bond, it is possible to selectively degrade the unsaturated fatty acids with multiple double bonds to a shorter chain length with a decrease in the unsaturation down, if desired, to mono-unsaturates, while the initially present mono-unsaturated fatty acids remain substantially unchanged. If, however, the unsaturated fatty acids present are to be converted as completely as possible into saturated fatty acids,

5 10 15 20 25 30 35 40 45 50 55 60 65 70

there is preferably employed a quantity of alkali hydroxide, which is at least 105 and preferably 120 to 200% of the quantity theoretically required. It is, of course, possible to use much higher quantities of alkali, as, for example, up to 400% of the amount theoretically required, but operation with such large excesses of alkali hydroxide is uneconomic, since the unnecessarily high excess of alkali used remains in the soap formed, and is destroyed upon the working up of the soap to fatty acids.

The alkalis used are preferably alkali hydroxides, and in particular sodium or potassium hydroxide or their mixtures.

The degradation reaction may be effected either in the presence or absence of water. When working without pressure, any water present in the reaction mixture evaporates practically completely, so that if the presence of water is desired, the use of pressure becomes necessary. The pressure in the reaction vessel generally establishes itself in accordance with the reaction conditions, and can, in general reach values of up to about 200 kg./cm.², though it is preferable to operate pressures between about 30 and 150 kg./cm.². The reaction may, of course, take place at still higher pressures, but for practical reasons pressures in excess of about 300 kg./cm.² are not used. If the hydrogen used is blown out of the reaction vessel during the reaction, care should be taken that the pressure does not drop below the vapor pressure of the water present in the reaction mixture if the reaction is to be effected in the presence of water. Operating in the presence of water has the advantage that the formation of non-saponifiable products during the reaction is extensively suppressed. For this purpose there is generally required a water content of at least 20% by weight referred to the fatty acid present in the reaction mixture, though amounts of water of about 50 to 100% by weight are preferably used. Although the reaction will still occur with higher dilution, operation is generally not effected with a water content of more than about 400% by weight. The pressures occurring during the reaction are dependent on the extent to which the reaction vessel is filled, or whether or not hydrogen is blown off during the reaction and upon the reaction of temperature used, which may rise, for example, to about 420° C. In general, it is not necessary to use temperatures above about 400° C., and, if operation is effected without pressure, and thus in the absence of water, it is generally not advisable to employ a reaction temperature above about 350° C.

The reaction is generally effected by merely heating the alkali soap of the fatty acid in the presence of the excess alkali hydroxide and the catalyst metal in accordance with the invention, as, for example, in a closed pressure vessel, such as an autoclave, and preferably with stirring. The alkali soap may be formed in situ by initially contacting the unsaturated fatty acid with an amount of alkali hydroxide sufficient to form the soap and leave the excess of alkali hydroxide required for the degradation. In general, the process may be effected using all the known embodiments of the Varrentrapp reaction, as, for example, those described in connection with French Patent No. 1,037,261.

The catalytic action of the catalyst in accordance with

the invention may already be noted upon the addition of 0.05% by weight metal, referred to the fatty acid present in the reaction mixture. It is preferable, however, to operate with larger quantities of catalyst, as, for example, 0.5 to 20% by weight metal, though larger quantities may be used, so that, for example, the metal used is present in equivalent amounts to the fatty acid present. It is also possible to use the entire fatty acid in the form of its salts with the catalyst metal, particularly when it is desired to separate the unsaturated fatty acid in the form of metal salts from the accompanying saturated fatty acids formed.

The catalysts used in accordance with the invention may be employed in the form of free metals or their compounds, and particularly in the form of compounds which are reduced under the reaction conditions to the free metals. Such compounds which, may be added to the reaction mixture, include, for example, the carbonates, bicarbonates, oxides, or hydroxides of lead, bismuth, or thallium. It is, of course, also possible to add the metal in the form of compounds which form hydroxides or oxides with the alkali hydroxide under the reaction conditions. These compounds include, for example, chlorides, bromides, iodides, sulfites, sulfates, phosphates, nitrates, nitrates, formates, acetates, oxalates, stearates, oleates, ricinoleates, benzoates, phthalates, benzene sulfonates, or paraffin sulfonates, as well as salts of other inorganic or organic acids, and in particular, the mineral acids or the carboxylic of sulfonic acids.

If the catalyst metals are amphoteric, they may also be used in the form of salts in which the metal is in the acid radical, as, for example, plumbites or plumbates in the case of lead. Complex salts of the metals can also be added. It is also possible to use metallorganic compounds, as, for example, tetraethyl lead, diphenyl lead or other metal alkyls or aryls as the catalytically active metal compounds.

The lead, bismuth and thallium or their compounds may also be used in combination with each other to particular advantage. The metals may also be used in the form of mixtures or alloys with each other or with other metals, and it is of particular advantage to use the metal in the form of a low-melting alloy, as, for example, an alloy having a melting point below the reaction temperature, as the same is of special advantage in connection with the recovery of the catalyst, since it allows separating the liquid metal from the reaction mixture, which is of great value, both in connection with continuous operation and batch operation.

It is, of course, possible, even when using the pure metal lead, thallium or bismuth, to operate above the melting points of the same (lead—327° C.; thallium—303° C.; and bismuth—271° C.), which, as a matter of fact has already been done in the case of cadmium (321° C.), but when operating in such a manner it is necessary to effect the separation of the liquid metal from the reaction mixture above its melting point, since otherwise the liquid metal may solidify at a different colder portion of the apparatus and result in clogging. When, however, operating with alloys which have melting points which are relatively far below the reaction temperature, it is possible to separate the catalyst even at lower temperatures in the liquid condition from the reaction mixture, the higher specific weights of said alloys promoting the separation, so that the liquid metals may easily be separated by allowing the same to settle out at the bottom of the vessel in question. The separation of the metal may be effected at any desired place, as, for example, in the reaction vessel itself, or in a special separator after dilution of the reaction mixture with water. The alloys separated from the reaction mixture may then either be recycled to the process as such, or after being worked up into metal compounds.

The catalyst metals in accordance with the invention form a large number of alloys with each other, with cadmium, or with catalytically inactive metals. The melting point of these alloys may lie above or below the melting

point of the catalytically active metal per se. There are preferably used, however, low melting point alloys, as, for example, those having melting points below 300° C., and preferably below about 200° C.

Among the alloys of lead, thallium, and bismuth, there is a particularly large number having low melting points, and in many cases melting points below 100° C. In accordance with the present invention there are used, for example, alloys of the systems

Pb+Bi, Pb+Tl, Pb+Cd
Bi+Tl, Bi+Cd, Tl+Cd
Pb+Bi+Tl, Pb+Bi+Cd, Bi+Tl+Cd
Pb+Bi+Tl+Cd

The metals to be used in accordance with the invention or their alloys can, however, also be combined with other metals which in themselves are inactive, for instance, with metals which melt at a lower temperature than the metals to be used in accordance with the invention, or with metals which melt at a higher temperature. This includes indium (156° C.), tin (232° C.) and antimony (630° C.). The following table contains metals or metal alloys having melting points below 300° C.

Metal or alloy (figures=percent by weight):	Melting point in ° C.
Bi	271
10-75 Pb, balance Sn	190-270
82.5 Pb+17.5 Cd	248
87 Pb+13 Sb	247
83 Tl+17 Cd	204
38 Pb+62 Sn	193
62 Bi+38 Cd	144
58 Bi+42 Sn	136
44 Pb+56 Bi	125
60 Bi+30 Cd+10 Tl	125
53 Bi+26 Sn+21 Cd	103
52 Bi+32 Pb+16 Sn	96
50 Bi+25 Pb+25 Sn	94
50 Bi+30 Pb+20 Sn	92
50 Bi+26.7 Pb+13.3 Sn+10 Cd	70
50 Bi+25 Pb+12.5 Sn+12.5 Cd	60
40.95 Bi+22.10 Pb+18.10 In+10.65 Sn +8.20 Cd	46

As alloys, there may be used alloys of two or more components, the composition of low-melting eutectics being preferably selected. Since, however, frequently slight additions of a foreign metal to a catalytically active metal are sufficient to considerably reduce the melting point of the latter, the use of eutectic mixtures is not absolutely necessary if it is desired to operate with a low melting mixture. Accordingly, the alloys can contain at least 5% by weight of the active metal to be used in accordance with the invention and preferably 10 to 95% thereof by weight. In case of the use of alloys, the quantities of catalyst given below refers to the quantity of the active component, to be used in accordance with the invention, present in the alloy.

The invention, however, does not extend only to the use of low-melting alloys, but also to the use of pure metals or alloys which melt at a higher temperature than the pure metals. When using such alloys it is possible to operate below the melting point of the metal and thus avoid the melting of the metal in the reaction mixture. The metal then remains suspended in finely divided form in the reaction mixture, and, after the dissolving of the reaction mixture in water, can be separated and added to new reaction batches.

The following examples are given by way of illustration and not limitation:

For the carrying out of the experiments described in the examples, there was used technical powdered sodium hydroxide containing about 6% by weight water. The composition of the batches used is indicated in the examples. The batches were filled into tubes of nickel

(Example 1), of V4a-steel (Examples 2-5) or copper (Examples 6 and 7), and placed, in these tubes, in an autoclave provided with an agitator. In the autoclave the batches were heated to the temperatures indicated. The autoclave remained closed during the entire reaction, so that neither water, which had formed upon the neutralization of the fatty acid with alkali hydroxide, nor which had been added to the reaction batch, nor hydrogen, could escape from the reaction batch. After cooling to room temperature, the autoclave was opened, the tubes containing the reaction product were removed, and the reaction product was dissolved in hot water. The catalyst metal collected to a large extent on the bottom of the tubes so that the solution of the reaction product in water could be directly poured off from the metal. From the aqueous solution the fatty acid was separated by hydrochloric acid and then washed neutral with water.

The tubes, the agitators of the autoclaves, and the thermometer connections were freed of small amounts of catalyst metal adhering thereto before each new test by treatment with dilute nitric acid.

Since the yields in connection with the process are practically quantitative, the yields were not determined in the individual experiments. However, the characteristic values of the degraded fatty acids were given.

Example 1

Batch:

500 grams soya fatty acid, refined (acid number =205, saponification number=209, iodine number=93, solidification point=28.7° C., unsaponifiables=1.2%)

158 grams NaOH

20 grams PbCl₂

Reaction:

4 hours at 300° C., maximum pressure 86 kg./cm.²

Fatty acid:

Acid number=200, saponification number=198, iodine number=36, solidification point=32.7° C.

Example 2

Batch:

300 grams fatty acid according to Example 1

102 grams NaOH

21 grams Bi(NO₃)₃·5H₂O

Reaction:

4 hours at 300° C., maximum pressure 82 kg./cm.²

Fatty acid:

Acid number=194, saponification number=201, iodine number=37, solidification point=32.7° C.

Example 3

Batch:

500 grams fatty acid in accordance with Example 1

170 grams NaOH

19.5 grams TiNO₃

Reaction:

4 hours at 300° C., maximum pressure 91 kg./cm.²

Fatty acid:

Acid number=193, saponification number=195, iodine number=34, solidification point=33.1° C.

Example 4

Batch:

300 grams fatty acid in accordance with Example 1

100 grams NaOH

16 grams KOH

20.2 grams PbCl₂

Reaction:

2 hours at 300° C., maximum pressure: 62 kg./cm.²

Fatty acid:

Acid number=206, saponification number=206, iodine number=31, solidification point=33.5° C., unsaponifiables=5.5%

When carrying out the same experiment without addition of catalyst, there was obtained a fatty acid having the following characteristic values:

Acid number=197, saponification number=200, iodine number=41, solidification point=33° C., unsaponifiables=8.2%.

Example 5

Batch:

500 grams soya fatty acid (acid number=187, saponification number=210, iodine number=103, solidification point=25.1° C., unsaponifiable matter=0.7%)

170 grams NaOH

29.2 grams PbCl₂ } Melting point of the catalyst
6.0 grams SbCl₂ } alloy: 250° C.

Reaction:

5 minutes at 300° C., maximum pressure: 64 kg./cm.²

Fatty acid:

Acid number=211, saponification number=219, iodine number=43, solidification point=27.8° C., unsaponifiables=3.0%

When the same batch, without catalyst, was heated for 4 hours at 300° C., there was obtained a fatty acid having the following characteristic values:

Acid number=198, saponification number=201, iodine number=34, solidification point=28.2° C., unsaponifiables=9.4%.

Example 6

Batch:

200 grams fatty acid according to Example 1

69 grams NaOH

214 grams water

35 12 grams Bi(NO₃)₃·5H₂O } Melting point of the
5.3 grams PbCl₂ } catalyst alloy: 92° C.
0.94 grams CdO

Reaction:

2 hours at 350° C., maximum pressure: 180 kg./cm.²

Fatty acid:

Acid number=226, saponification number=226, iodine number=22.6, solidification point=32.1° C., unsaponifiables=2.1%

Example 7

Batch:

250 grams technical oleic acid (acid number=197, saponification number=202, iodine number=82, solidification point=6° C., unsaponifiables=0.8%)

80 grams NaOH

8 grams water

15 grams Bi(NO₃)₃·5H₂O } Melting point of the
6.6 grams PbCl₂ } catalyst alloy: 127° C.
1.2 grams CdO

Reaction:

2 hours at 350° C., maximum pressure: 98 kg./cm.²

Fatty acid:

Acid number=209, saponification number=209, iodine number=33, solidification point=33.6° C., unsaponifiables=4.7%.

Upon carrying out the same experiment without catalyst, there was obtained a fatty acid having the following characteristic values:

65 Acid number=179, saponification number=181, iodine number=23, solidification point=31° C., unsaponifiables=19.0%.

We claim:

1. In the method for degrading unsaturated fatty acids, in which an alkali salt of an unsaturated fatty acid, free from alcoholic hydroxyl groups is heated in the presence of an alkali hydroxide, the improvement which comprises effecting the heating in the presence of at least 0.05% by weight a catalyst based on said fatty acid selected from the group consisting of lead, bismuth,

thallium, mixtures thereof, alloys thereof and compounds of said metals and in which said heating is effected at a temperature of about 300° C.

2. Improvement according to claim 1 in which said metal compound is a member selected from the group consisting of metal chlorides and metal nitrates.

3. Improvement according to claim 1, in which said group member is present in amount of about .05 to 20% by weight, based on said fatty acid.

4. Improvement according to claim 1, in which said group member is in the form of an alloy having a melting point below the temperature to which said heating is effected.

5. Improvement according to claim 4, which includes separating said group member from the reaction mixture in the liquid state.

6. Improvement according to claim 5, which includes recycling the separated group member.

7. Improvement according to claim 6, which includes

converting said separated group member to a metal compound prior to said recycling.

8. Improvement according to claim 1, in which said group member is initially added in the form of a metal compound.

9. Improvement according to claim 1, in which said alkali hydroxide is a member selected from the group consisting of sodium hydroxide, and potassium hydroxide.
